DISPENSING CIGARETTE CASE WITH
EJECTOR LOCKING MEANS

Vincent Pino, New York, N.Y.

Application April 12, 1946, Serial No. 661,775

2 Claims. (Cl. 206—41.2)

1

This invention relates in general to a cigarette case and in particular to an ejecting cigarette case for automatically dispensing cigarettes one at a time as required.

According to this invention, there is provided a novel cigarette case which is adapted to contain and store cigarettes for carrying, which is adapted to dispense the cigarettes quickly and easily in a convenient manner as they are desired. Accordingly it is an object of this invention to provide an ejecting cigarette case for dispensing cigarettes individually.

It is another object of this invention to provide a smoker's article comprising a case adapted to receive cigarettes or the like having a hinged cover and having means for dispensing individual cigarettes contained therein.

Additional objects of this invention as well as its construction, use and operation will in part be obvious and will in part become apparent from the following disclosure.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure—

Fig. 1 is a perspective view of a cigarette case according to one form of this invention.

Fig. 2 is a perspective view of the article shown in Fig. 1 in the open condition.

Fig. 3 is a top plan view of the article shown in Fig. 2.

Fig. 4 is a top cross section of the article shown in Fig. 2 taken along the line 4—4.

Fig. 5 is a partial and elevational view of the case of a cigarette container constructed in accordance with a modification of the present invention.

Fig. 6 is a similar view of the article shown in Fig. 5 with the catch member removed.

Fig. 7 is a rear perspective view of the catch member shown in Fig. 5.

Fig. 8 is a perspective view of a combination cigarette case and compact according to a further form of this invention.

Referring to the figures in detail there is shown in Figs. 1 to 4 a cigarette container generally designated 10 comprising a case 11 having a hinged cover 12 and a snap fastener 13 and 13a. The space within the case 11 is adapted to retain a number of cigarettes 14 in side-by-side position. A retaining member 15 passes across the top of

case 11 and is adapted to hold the cigarettes 14 in their correct position. The case 11 has two side or end walls 16 and 17 which extend the full depth of the case and to which member 15 is secured. Across the front of case 11 is a relatively low front wall 18 roughly half or less than half the height of wall 16 or 17. This front wall 18 terminates short of side wall 17 leaving a gap between wall 16 and wall 17 substantially the width of an ordinary cigarette, the gap being adapted to permit passage therethrough of one of the cigarettes 14.

Extending across the case 11 from the front to back thereof is a contact bar 19 which lies parallel with cigarettes 14 and which is adapted to bear thereagainst. This contact bar 19 is slidably mounted on a rail or bar 20, the rail in turn being mounted between walls 16 and 17. Resilient means, as will be described hereinafter, cause contact bar 19 to be constantly urged into contact with cigarettes 14 thus continuously forcing the cigarettes against end wall 17. Thus at all times one of the cigarettes 14 is positioned adjacent the gap between wall 18 and wall 17 and is adapted to be slid therethrough.

The cover 12 comprises a cover member 21 hingably mounted on case 11 and a flap 22 mounted to the cover member 21 and adapted to cover the front of the case, preferably lying against wall 18 when the cover is closed. At one end of flap 22 adjacent wall 17 is an opening 24 of a size and shape to permit free passage of one of cigarettes 14 therethrough. This opening 24 is so positioned that it is directly in line with the end cigarette 14a within the case and likewise directly in line with the gap between walls 17 and 18.

Optionally positioned on the inside of cover member 21 is a mirror 25 or other similar decorative and useful article.

Running along side wall 17 and parallel to the position of cigarettes 14 is a slot 26. An ejector 27 is mounted inside wall 17 by means of a stem 28 and a handle 29 which project through and secure to slot 26. The ejector 27 comprises a wall piece 30 which is adapted to rest against the inside of wall 17 and two spaced ejector walls 31 and 32 mounted at right angles to wall 30. Wall 31 extends from wall 30 for a distance not longer than the diameter of one of cigarettes 14a, preferably somewhat less than the diameter of the cigarette, that is, about one quarter of an inch.

This wall 31 is adapted to bear against the end of cigarette 14a and as the ejector 27 is moved toward opening 24 wall 31 forces cigarette

14^a through the opening. The resilient member 33 is secured to wall 32 and is adapted to return ejector 27 to its starting position as shown in Fig. 4.

The ejection operation is accomplished simply by forcing handle 28 in a direction toward opening 24, the motion being imparted to wall 30 through stem 28. When ejector 27 is subsequently returned to this starting position as shown in Fig. 4, contact bar 19 which is constantly bearing against cigarettes 14 immediately forces the next cigarette into the position originally occupied by the end cigarette 14^a and the ejector device is ready for a subsequent similar operation. The operation of the device is shown clearly in Fig. 4 which indicates a resilient member 33 secured to wall 32 of ejector 27 and secured at its other end to wall 16. This resilient member 33 optionally passes around a post 34 mounted on the case 11 so that its resilient force is exerted in the correct direction. Likewise a second resilient member 35 is secured to contact bar 19 and passes around a post 36 to be secured at its other end to wall 16. Thus there is a constant force acting on contact bar 19 urging it toward wall 17 and at the same time the constant force urging ejector 27 to its starting or rest position.

For purpose of more attractive design the greater portion of resilient members 33 and 35 will be contained behind a housing wall 37 at the rear of case 11.

The resilient members 33 and 35 may be constructed of any desired material such as, elastic rubber, a metal spring or the like. A particular structural material will be optional and within the ability of those skilled in the art to select. Except where unusual wearing qualities are necessary or where the device is to be exposed to unusual temperature or humidity conditions, members 33 and 35 will generally be constructed of an elastic rubber or rubber substitute material.

It will be understood that numerous changes in structure and design may be made in the article described herein without departing from the scope of the invention. For example, the size and the shape of the container may be varied to accommodate cigarettes of various sizes and likewise the design of the container may be modified for decorative purposes. The container may be constructed of numerous materials such as wood, metal, hard rubber, plastic and the like.

In Figs. 5 to 7 there is shown a locking means which is adapted to be used in connection with the article described herein to discourage meddling or tampering with the device. The locking means comprises a device adapted to retain stem 28 in position half way between its raised position as shown in Fig. 4 and its ejection position shown in dotted outline in Fig. 4. Thus for example, the ejector 27 may be moved to eject cigarette 14^a and then return by the way of its original position, there to be locked in position preventing further operation until the locked means is released.

The locking means shown in Figs. 5 to 7 comprises a catch member 38 secured adjacent to slot 26 on wall 17 and a recess 39 in slot 26 adjacent to catch member 38. Catch member 38 comprises a body 39' having a finger 40 extending from one end thereof and having a guide rail 41 on its rear surface. Optionally, a button or handle 42 on the front surface of catch member 38 allows more convenient operation thereof. Along the lower edge of slot 26 is a recess 39

and a narrow guide slot 43 running parallel to main slot 26. Guide rail 41 on catch member 38 is adapted to slide within guide slot 43 whereby the catch member 38 may be moved a short distance parallel with slot 26. In the operating condition finger 40 on guide member 38 is adapted to close off recess 39 or to open recess 39 to slot 26 as the catch member 38 is moved back and forth. Thus catch member 38 may be moved back, stem 28 of ejector 27 moved into recess 39, and catch member 38 moved to close off recess 39 thereby retaining stem 28 therewithin as illustrated by the dot and dash lines 28^a in Fig. 5. This effectively controls the operation of the device and discourages meddling by unauthorized persons. The locking means is quickly and easily opened by sliding catch member 38 and removing stem 28 from recess 39.

In Fig. 8 there is shown a further form of the invention comprising a case 11^a having a cover 12^a, the cover having a flap 22' and a hole 24^a as in the previous form of the invention. In this form of the invention there is a contact bar 19^a, a retaining member 15^a, a guide rail 20^a and other members as described and numbered in connection with Figs. 1 to 4.

In addition to the purposes described hereinbefore, the article 10^a shown in Fig. 8 is a ladies' compact in combination therewith. To the side of wall 16, which serves the boundary of the cigarette case portion of the article, there is a space or chamber 44 bounded by front wall 18^a to the case 11^a, wall 16, side or end wall 16^a, and rear or housing wall 37. This chamber 44 has a center or dividing wall 45 to divide into at least two compartments for containing powder, rouge, or other cosmetic needs. On the inside of cover member 12^a there are optionally mounted a mirror 25^a or the like and a picture or picture frame 25^b or the like.

The use and operation of the device according to this form of the invention is similar to the use and operation description hereinbefore in connection with Figs. 1 to 4 and the locking means shown in Figs. 5 to 7 may optionally be added thereto.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a dispensing container having a case formed adjacent one end wall with an opening through which a cigarette can be endwise dispensed and a slidable ejector within the case for moving the cigarette endwise through the opening, means for locking the ejector in a fixed position within the casing, comprising a stem projected laterally from the side of the ejector, the said one end wall being formed with an elongated slot through which said stem may project to be moved along the length of said slot to move the ejector in a direction to eject the cigarette, said slot continuing along one side intermediate of its ends into a recess engaged by said stem for holding the ejector against sliding movement, a catch member slidably mounted on the said one end wall adjacent one end of said recess to be movable toward and away from said recess, a finger formed on the

end of said catch member adjacent said recess and extended across said recess between said slot and said stem retaining said stem in said recess, whereby when said catch member is moved in a direction away from said recess said finger moves clear of said recess freeing said stem to be moved out of said recess into said slot so that said stem can be moved along the length of said slot.

2. In a dispensing container having a case formed adjacent one end wall with an opening through which a cigarette can be endwisely dispensed and a slideable ejector within the case for moving the cigarette endwisely through the opening, means for locking the ejector in a fixed position within the casing, comprising a stem projected laterally from the side of the ejector, the said one end wall being formed with an elongated slot through which said stem may project to be moved along the length of said slot to move the ejector in a direction to eject the cigarette, said slot continuing along one side intermediate of its ends into a recess engaged by said stem for holding the ejector against sliding movement, a catch member slidably mounted on the said one end wall adjacent one end of said recess to be movable toward and away from said recess, a finger formed on the end of said catch member adjacent said recess and extended across said recess between said

slot and said stem retaining said stem in said recess, whereby when said catch member is moved in a direction away from said recess said finger moves clear of said recess freeing said stem to be moved out of said recess into said slot so that said stem can be moved along the length of said slot, said finger and said catch member having their sides, which are opposed to the side of the finger which engages said stem when in said recess, flush with the adjacent side of said slot so as not to interfere with movement of said stem along the length of said slot.
